UNITED STATES PATENT OFFICE.

JOHN SKABA, OF BRAIDWOOD, ILLINOIS, ASSIGNOR OF ONE-HALF TO JAMES JIRUS, SR., OF BRAIDWOOD, ILLINOIS.

SAFETY-STOP FOR ELEVATORS.

950,459.

Specification of Letters Patent. Patented Feb. 22, 1910.

Application filed April 19, 1909. Serial No. 490,858.

To all whom it may concern:

Be it known that I, JOHN SKABA, a citizen of the United States, residing at Braidwood, in the county of Will and State of Illinois, have invented certain new and useful Improvements in Safety-Stops for Elevators, of which the following is a specification.

This invention relates to the class of elevators used in buildings and mine shafts; and has for its object to provide a safety device that will automatically arrest the movement of elevator car and prevent the same from dropping should the cable be accidentally broken.

Figure 1 is an elevation. Fig. 2 is a horizontal section on line 2, Fig. 3, a portion of the car floor being broken away. Fig. 3 is a vertical section on line 3, Fig. 2. Fig. 4 is a vertical section on line 4, Fig. 2, showing the locking bolts in their engaged position. Fig. 5 is a similar view, showing the bolts in their disengaged or normal position.

The framed-sides lining the elevator shaft, and consisting of the uprights A and the horizontal connecting pieces B, may be of any or the usual form of skeleton frame construction and will not be described in detail.

C may represent the elevator car, D the vertical guides therefor, and E the main elevator cable. The elevator cable E is in this instance connected to a ring 6, as shown in Fig. 1. Two branch cables 7 extend from this ring to opposite sides of the car and connect with a rigid part thereof. The branches 7 are a continuation of the elevator or suspension cable E. Two other branch cables 8 connect the ring 6 and a cross-bar 9, which actuates the locking mechanism. The cross-bar 9 is located over the top of the car and normally is spaced apart therefrom, as best shown in Figs. 3, 4 and 5. The companion cords 10 are secured to the respective ends of the cross-bar 9 and extending downward therefrom, the lower end of each connecting with the outer end of an arm 11 mounted on a rock-shaft 12 near its longitudinal center, as best shown in Fig. 2.

It will be understood that the locking mechanism is in duplicate and located on opposite sides at the bottom of the car; the same reference characters being used on

duplicate parts. In this instance two locking-bolts 14 and 15 are used and which are located at opposite sides, as best shown in Fig. 2. The inner ends of the locking-bolts are each secured to a bifurcated member 16, the outer free ends being adapted to engage any of the horizontal stop-bars 17 forming a part of the frame-work lining the elevator shaft. These stop-bars are disposed at intervals of approximately six inches so that should the cable break or become slack the car will move but a short distance before the bolts 14 and 15 will be thrown into a locking engagement and the descent of the car arrested. The links 19 form an operative connection between the rock-shafts 12 and the bifurcated members 16. A rod 20 connects the inner ends of the members 16, and has one end of a spring 21 secured thereto. The opposite end of this spring or springs is secured to a stationary part of the car. When the elevator cable is taut the strain, through the medium of the cross-bar 9 and the cords 10, holds the arms 11 up against the under side of the car as shown in Figs. 3 and 5. Corresponding to this position the bolts 14 and 15 are retracted from their locking position and the springs 21 expanded, as shown in Figs. 2 and 3. Should an accident happen to the cable so that it does not control the movement of the car, the cross-bar 9 will drop and the strain on the cords 10 be relaxed when the springs 21 on opposite sides will have the effect of shooting the bolts into their engaged locking position and the car prevented from dropping. When the car is again suspended on its cables the cords 10 are drawn taut and the bolts retracted from their position against the tension of their operating springs and leaving the car free to move in either direction.

This arrangement provides a safety means that is positive and direct in operation and guards against the possibility of accidents.

Having thus described my invention, what I claim is—

In a device of the character described, the combination with an elevator car and its shaft, of a plurality of stop members located at the sides of the shaft, a suspension cable, connections between said cable and the elevator car, a cross bar extending across the top of the elevator car, a rock shaft located upon each side of the elevator car and under the

bottom thereof, an operating arm carried by each of said shafts, connections between said arms and said cross bar, a pair of bolt actuating arms carried by each rock shaft, a pair of bolts connected to each of said pairs of arms, a connecting member extending between each pair of bolts, and a spring connected to each connecting member and to a

portion of the elevator car, whereby each spring actuates a pair of said bolts. 10

In testimony whereof I affix my signature in presence of two witnesses.

JOHN SKABA.
